UNITED STATES PATENT OFFICE.

GIDEON SIBLEY, OF PHILADELPHIA, PENNSYLVANIA.

DENTAL TOOL.

SPECIFICATION forming part of Letters Patent No. 416,426, dated December 3, 1889.

Application filed June 18, 1888. Serial No. 277,418. (No model.)

To all whom it may concern:

Be it known that I, GIDEON SIBLEY, a citizen of the United States, residing at the city and county of Philadelphia, and State of Pennsylvania, have invented certain new and useful Improvements in Dental Implements, of which the following is a full, clear, and exact description, reference being had to the accompanying drawings, of which—

10 Figure 1 is a side elevation. Fig. 2 is a longitudinal sectional elevation of the working end thereof, enlarged, the pin being shown in its normal or projected position. Fig. 3 is a similar view, with the pin retracted. Fig. 15 4 is a perspective view of the working end of the implement.

The nature and object of this invention is a dental implement for picking up gold or other filling materials and conveying the same 20 to the cavity in the tooth to be filled, and also adapted for plugging or working the filling into the cavity. Heretofore it has been customary to pick up the filling and convey it to the tooth, either by a pair of pinchers or the 25 usual serrated working end of the plugging-tool, the latter being pressed down upon the gold, &c.; but the manipulation by the pinchers was slow, and the serrations could not be always relied upon for retaining the gold, &c.; 30 and with both devices the filling was apt to become somewhat condensed before its insertion in the tooth-cavity.

My improvement avoids these objections; and it consists, generally, of a suitable handle—such as is common in dental filling-tools—having combined therewith at its small or operating end a movable sharp-pointed pin or needle, whose point is adapted to be projected a short distance beyond said operating end, 40 and to be retracted so as not to thus project, whereby the gold, &c., may be readily picked up by pressing the point of the pin into the same, (the pin retaining the gold by its friction,) conveyed to the tooth and released 45 when inserted by the retraction of the pin.

The invention consists, further, in the combination, with the devices just recited, of a spring for keeping the point of the pin normally projected beyond the operating end of 50 the implement, but allowing its easy retraction, as hereinafter described.

The invention further consists in certain

special details of construction, which will be hereinafter described and duly claimed.

I shall now proceed to describe that which 55 I consider the most desirable form and construction of the invention.

Referring to the annexed drawings, A is a handle—such as is usual in dental filling-tools—with its small or working end a preferably, but not necessarily, at an angle thereto, as shown. This end is perforated centrally and contains a movable needle-pointed pin B, preferably of steel, the point b' being kept normally projected—say, one-sixteenth 60 of an inch—by means, in the present instance, of a flat spring C, which is secured to the handle by screws b² and bears against the head of the pin. The hole a² in the head a' has an offset a³ therein against which abuts 65 a corresponding shoulder b², formed on the pin B. Thus the projection of the pin is limited. When the head a' is inclined, as shown, I prefer to give the adjacent part of the handle a bend, as at a⁴, and to correspondingly bend 70 the free end of the spring C, whereby a more direct pressure is exerted by the spring upon the pin.

In using the implement the pin end is 75 pressed down upon the gold or other filling 80 material, and the pin will enter the latter, and, owing to the friction, the material will be picked up when the tool is raised, and may be conveyed to the cavity in the tooth and then pressed into the latter by means of the 85 working end a', through which the pin projects. The filling is not drawn out by the 90 pin in the plugging operation, as the hold of the former in the cavity into which it has been forced is greater than that—*i. e.*, the friction—of the pin, and the pin, retracting under slight pressure, is not forced into the already-compacted filling by the pressure of the end of the implement during the operation. 95

I remark that the end of the implement is or may be serrated, as is customary in dental plugging-tools.

I do not limit myself to the special construction shown and described, as the device may be variously modified without departing from the essential principle thereof—as, for example, in lieu of the spring for projecting the pin-point I may use a pivoted arm or lever

connected with the pin and adapted to be operated by the finger to project or retract the pin-point; and, again, instead of the flat spring shown a spiral spring may be used; 5 and, also the pin may be straight or in line longitudinally with the handle instead of inclined with respect thereto.

Having thus described my invention, I claim as new and wish to secure by Letters Patent—

- 10 1. In a dental plugging or filling implement, the combination of the handle and the movable needle-pointed pin at the working end thereof, said pin projecting slightly beyond said working end, so as to readily pick up the filling material when pressed down, and then be retracted, so as to release the latter and thereby permit the said working end to be used to force the filling into the cavity of the tooth, substantially as described.
- 15 2. In a dental plugging or filling implement,

the combination of the handle, the movable needle-pointed pin at the working end thereof, and the spring adapted to normally project said pin slightly beyond said working end, substantially as described.

25

3. In a dental filling or plugging implement, the combination of the handle provided with the inclined perforated end, and the offset or bend a^4 , the pin contained in said end, and the flat bent spring C, secured to the handle 30 and bearing against said pin, substantially as and for the purpose set forth.

In testimony whereof I have hereunto affixed my signature this 12th day of June, A. D. 1888.

GIDEON SIBLEY.
